SLUR-PREVENTING MECHANISM FOR
PRINTING PRESSES

Glen N. Krouse, Columbus, Ohio

Application January 19, 1944, Serial No. 518,855

6 Claims. (Cl. 101—420)

This invention relates to an improved slur-preventing mechanism for use in conjunction with printing presses, particularly printing presses of the reciprocating bed and oscillating cylinder type.

An object of the invention is to provide simple, positive and efficient means for precluding undesired wiping contact between the paper or paperboard sheet undergoing printing and the last line of type of the chase or form, whereby to overcome blurring of the printed impressions on the trailing edge of the sheet.

The mechanism forming the present invention is used in the printing industry to prevent what is known as "slur," a word used to describe the misplaced ink caused by sliding of the free or trailing end of the paper being printed on the ink type. The prevention of slur has been a problem with printers for years, and has been tediously eliminated in practice by driving tacks at the edge of the last line of type held in a chase or form. Such an operation is makeshift at best and consumes considerable costly time. In accordance with the present invention, an automatic mechanism is provided in conjunction with the reciprocating type bed whereby when impressions are printed on a paper sheet by the last line of type of the bed or chase, the trailing edge of the paper is lifted automatically from engagement with the type, preventing sliding of the paper and thereby overcoming the cause of slurring.

For a further understanding of the invention, reference is to be had to the following description and the accompanying drawing, wherein:

Fig. 1 is a fragmentary plan view of the reciprocating type bed of a printing press, and illustrating the slur-preventing means, forming the present invention, in association therewith;

Fig. 2 is a detail vertical sectional view on an enlarged scale disclosing the slur-preventing means in the type bed and illustrating the sheet-lifting fingers in their lowered or inactive positions;

Fig. 3 is a similar view taken on the plane disclosed by the line 3—3 of Fig. 1;

Fig. 4 is a transverse vertical sectional view on the line 4—4 of Fig. 3;

Fig. 5 is a vertical longitudinal sectional view on the line 5—5 of Fig. 1;

Fig. 6 is a vertical sectional view, similar to Fig. 2, but illustrating the sheet-lifting fingers in their elevated or active positions;

Fig. 7 is a vertical transverse sectional view on the line 7—7 of Fig. 1.

Referring more particularly to the drawing, the numeral 10 designates the frame-mounted reciprocating type bed or chase of a conventional printing press, and the numeral 11 designates the tympan-carrying oscillatory cylinder, the cylinder being geared, as usual, in connection with the bed or chase, so that as the latter reciprocates, rocking motion is imparted to the cylinder.

10 Clamped within the chase adjacent to the last line of type 12 thereof is the slur-preventing mechanism M forming the present invention. This mechanism, in the preferred embodiment thereof illustrated in the drawing, comprises a bar 13 having its upper surface longitudinally grooved as at 14. Positioned in this groove, and substantially coextensive with the length thereof, is a half round rocker member or rod 15. This member is adapted to oscillate about its longitudinal axis and is held in the groove 14 by means of pins 16, the latter having curved upper ends 17 which engage with the flat upper surfaces 18 of the rocker member at a position substantially in registration with its longitudinal axis, so that while the pins 16 prevent the rocker member from moving upwardly in the groove of the bar 13, they do not interfere with limited rocking movement of said member. The shanks of the pins 16 are received within vertical sockets 19 provided in the bar 13, and set screws 20, mounted in threaded openings 21 formed transversely in the bar 13, may be used to secure frictionally the pins in their operative positions.

At one end, at least, the rocker member 15 is 35 provided with a longitudinally projecting eccentrically disposed pin 22, which is received within a slot 23 provided in a vertically movable plunger 24. This plunger is mounted within the bed or chase 10 at one end of the rocker member 15, and is maintained normally in an elevated position by the use of a leaf spring 25. The latter is secured by means of the screws 26 to the under side of the bar 13, and the free end of said spring engages with a recess 27 in the lower end 40 of the shank 28 of said plunger, thereby holding in an elevated position the laterally enlarged T-shaped head 29 of the plunger in a plane above the upper surface of the bar 13. The upper surface of said bar is provided at longitudinally 45 spaced intervals with a plurality of resilient wire sheet-lifting fingers 30 which, as shown in Fig. 2, are normally disposed in a plane below the printing surfaces of the type 12, the fingers being secured in operative association with the bar 13 by means of the headed screws indicated at 31.

In the operation of the apparatus, consideration will disclose that when a sheet of paper or paperboard 33 is passed between the cylinder 11 and the type 12, the lifting fingers 30 will occupy their lowered or inactive positions removed from engagement with the sheet. However, as the trailing edge 34 of said sheet reaches a position where the last line of type imparts an impression thereto, the head of 29 of the plunger 24 is engaged by the periphery of the cylinder 11. Such engagement results in the depression of the plunger against the resistance exercised by the spring 25. This downward movement of the plunger imparts an oscillatory or rocking motion to the member 15, as a result of the eccentric location of the pin 22 and its position in the slot 23 of the plunger shank. The rocking movement thus imparted to the member 15 effects the elevation of the trailing edge of the paper sheet, bringing said fingers into their active positions and lifting the trailing edge of the paper sharply from the last line of type, thereby overcoming blurring or slurring which so frequently occurs in the average printing press when the trailing edge of the paper sheet slides over the last line of type. The fingers 30 press the trailing edge of the paper sheet against the tympan surface of the cylinder 11, holding the sheet firmly so that its trailing edge will not have wiping engagement with the last line of type in the chaser form. Since the fingers 30 are resilient, the same may be flexed by the action of cylinder 11 without injury, such flexing serving to increase their clamping action on the paper sheet. The construction of the slur-preventing mechanism is such that it does not in any way interfere with the inking of the type surfaces nor in any way interfere with any other normal press operations, its only function being to eliminate slur.

Having thus described my invention, what I claim is:

1. In a printing press, a reciprocable type-holding chase and a sheet-advancing cylinder arranged over the type contained within said chase, a rocker member supported by said chase contiguous to the last line of type carried thereby, resilient sheet-lifting fingers fixed to said rocker member, and means actuated by said cylinder when the latter is in registration with the last line of type in said chase for rocking said member and elevating the resilient fingers carried thereby to maintain the trailing edge of a paper sheet disposed between the type and cylinder in spaced relation from said last line of type.

2. The combination with a type form containing set-up type, of a stationary bar within said form, a movable non-printing rocker bar mounted on said stationary bar, a plurality of spaced-apart resilient fingers having certain of the ends thereof fixed to said rocker bar, a cylinder; and means actuated by said cylinder during the passage of the type form thereunder for oscillating said bar and thereby effecting the elevation of said fingers.

3. The combination with a printing couple comprising a reciprocable bed for carrying the form and a cylinder for carrying the sheet to be printed; of a type form containing the type and a slur eliminator disposed in said form comprising a fixed bar having a longitudinal groove in its upper surface, a rocking bar disposed longitudi-

nally in said groove for oscillating movement, a plurality of spaced-apart resilient fingers carried by said rocking bar, a spring-pressed plunger engageable with said cylinder during the passage of said form thereunder to produce vertical movement on the part of said plunger, and eccentric means operable to effect oscillation of said rocking bar when said plunger is depressed by said cylinder.

4. Slur-eliminating mechanism for printing presses comprising a stationary bar adapted to be locked in a type-containing chase, a rocker bar mounted for oscillation on the upper longitudinal surface of said stationary bar, resilient lifting fingers carried by said rocker bar and projecting laterally therefrom, a compressible plunger carried by said chase contiguous to said stationary bar, and means operable when said plunger is depressed to impart oscillating motion to said rocker bar and the fingers carried thereby.

5. Chase carried slur-eliminating mechanism for printing presses comprising a stationary bar having a longitudinally grooved upper surface, a semi-cylindrical rocking member having its rounded outer surfaces disposed longitudinally in the groove of said stationary bar, a plurality of resilient sheet-lifting fingers having the inner ends thereof fixed to the plane upper surface of said rocking bar, a substantially T-shaped plunger having the vertical shank thereof disposed for vertical sliding movement adjacent to one end of said stationary bar, resilient means carried by said stationary bar and serving to maintain said plunger in an elevated position, the shank of said plunger being provided with a transverse slot, and an eccentrically disposed pin projecting longitudinally from one end of said rocking bar and arranged within the slot of said plunger, whereby when said plunger is depressed, oscillating motion is imparted to said rocking member and the lifter fingers carried thereby.

6. Chase carried slur-eliminating mechanism for printing presses comprising a stationary bar having a longitudinally grooved upper surface, a semi-cylindrical rocking bar having the rounded outer surfaces thereof positioned in said groove, a plurality of resilient lifting fingers having the inner ends thereof stationarily secured to the flat upper surface of said rocking bar, the free ends of said fingers projecting laterally and upwardly from the rocking bar, pins carried by said stationary bar, said pins having hook-shaped upper extremities engageable centrally with the flat upper surfaces of said rocking bar to maintain the latter in the groove of said stationary bar, a vertically movable plunger having an elongated horizontally disposed head portion arranged above said stationary bar, a centrally disposed depending shank supported for vertical sliding movement at one end of said stationary bar, spring means carried by said stationary bar and engageable with the shank of said plunger to yieldably maintain the same in an elevated position, and an eccentrically arranged pin projecting longitudinally from one end of said locking bar and positioned in a slot provided in the shank of said plunger, whereby when said plunger is depressed, oscillatory motion is imparted to said rocking bar and the resilient fingers carried thereby.

GLEN N. KROUSE.
